UNITED STATES PATENT OFFICE.

CYRUS LENHART, OF BROOKFIELD, MISSOURI.

CAR-CO尤PLING.

SPECIFICATION forming part of Letters Patent No. 431,902, dated July 8, 1890.

Application filed February 27, 1890. Serial No. 341,986. (No model.)

To all whom it may concern:

Be it known that I, CYRUS LENHART, a citizen of the United States of America, residing at Brookfield, in the county of Linn and State 5 of Missouri, have invented certain new and useful Improvements in Car-Couplings, of which the following is a specification, reference being had therein to the accompanying drawings.

10 This invention pertains to certain new and useful improvements in car-couplings; and it comprises the detail construction, combination, and arrangement of parts, substantially as hereinafter fully set forth, and particularly 15 pointed out in the claims.

In the accompanying drawings, Figure 1 is a view in perspective of my improved coupler, shown attached to a car, the latter being in dotted lines, with parts broken away. Fig. 2 20 is a longitudinal sectional view. Fig. 3 is a view of the coupling-bar. Fig. 4 is a bottom plan view thereof, showing operating-levers.

Referring to the drawings, A designates the draw-head; a, a lower jaw pivoted at its center on a stud a' by a cross-pin a², and a³ a spring rigidly secured at one end to the draw-head and bearing upon the inner rear end of said jaw.

B is the coupling-bar, the hooked ends of 30 which may be both made with straight sides, as shown at b, or one of said ends may have rounded edges, as shown at b', whereby in the event of the accidental turning over of a car the rounded ends will readily slide over the 35 hooked end of the lower jaw and permit the cars to readily uncouple. The end of this coupling-bar upon striking against the outer end of a lower jaw will force the same open and enter the chamber b² of the draw-head, 40 wherein it will be held by the closing of said jaw.

C is a lever secured to the under side of the car and extended to the roof thereof. The inner end of this lever has a bent arm d, which bears against the under side of the rear end 45 of jaw a, whereby the latter can be opened to uncouple the cars. In lieu of this lever a lever C' may be employed capable of operation from the car-platform. This lever has a bent portion d', which also bears against 50 jaw a. (See Fig. 4.)

In the draw-head A above chamber b² is formed a second chamber e, wherein the connecting-link of an ordinary coupling may be secured by a pin e', placed in a hole e². By this 55 means a car provided with my improved coupling can be readily connected with a car having the old form of link-connection.

A car-coupling as thus constructed is extremely simple, cheap, and durable, and as it 60 comprises but few parts will not readily get out of order or become deranged.

I claim as my invention—

1. In a car-coupling, the draw-head having a lower chamber b², a jaw a, an upper chamber e, and a pin e', substantially as set forth. 65

2. In a car-coupling, the combination of the draw-head having a chamber b² in its lower portion; the jaw fulcrumed to said draw-head and having a forward hooked end, a spring 70 bearing on the rear end of said jaw, and the lever C, secured to the car and bearing against the under side of the rear end of said jaw, substantially as set forth.

In testimony whereof I affix my signature 75 in presence of two witnesses.

CYRUS LENHART.
